Primary Examiner — Mary Ann Calabrese*Assistant Examiner* — Jennifer L Rempfer(74) *Attorney, Agent, or Firm* — Birch, Stewart, Kolasch & Birch, LLP(57) **CLAIM**

The ornamental design for a speaker with lighting, as shown and described.

DESCRIPTION

1. Speaker with lighting
 1.1 is a perspective view of a speaker with lighting, showing our new design;
 1.2 is a front elevation view thereof;
 1.3 is a rear elevation view thereof;
 1.4 is a left-side elevation view thereof;
 1.5 is a right-side elevation view thereof;
 1.6 is a top plan view thereof;
 1.7 is a bottom plan view thereof;
 1.8 is another perspective view thereof, showing a first state of use;
 1.9 is another perspective view thereof, showing a second state of use; and
 1.10 is another perspective view thereof, showing a third state of use.

The broken lines represent environment of the speaker with lighting that form no part of the claimed design.

1 Claim, 10 Drawing Sheets(56)
